UNITED STATES PATENT OFFICE

JOHN BARLETTA, OF GALT, CALIFORNIA

COMBUSTION ENGINE

Application filed August 27, 1923. Serial No. 659,605.

One of the objects of my present invention is to provide a combustion engine with simple means for self-ignition, when using crude oil as fuel.

Another object of the invention is to provide simple means for making a two cycle engine adaptable to speed variation without misfiring.

To the attainment of the foregoing, the invention consists of improvements which are hereinafter described and definitely claimed.

The accompanying drawings show the improvements in the combustion engine, but I believe that the said drawings are sufficient to make clear the invention in which a reference numeral is applied to designate the same part throughout, but I am aware there may be modifications thereof.

Figure I is a transverse sectional view of the engine showing the interior mechanism.

Figure II is a sectional view of the auxiliary cylinder showing the piston, the eccentric gears for driving the piston at high speed and the air passageways.

In Figure I, number 3 is the combustion cylinder, 4 the enlargement of cylinder 3 forming a larger air cylinder for the scavenging cylinder 3, 5 the air tight crankcase, 50 the cylinder head, 6 the combustion piston, 51 the rings, 7 the enlargement of piston 6 to fit the air cylinder 4, 52 the rings adapted to create a low compression in the crankcase 5, 8 the projection slide extending from a portion of piston 7 with the port opening 10 to transmit air to one of the air passageways at the time it registers with 17 and 18. The port 49 opens the upper end of the air cylinder 4 free to the atmosphere and releases it from compression at all times, 9 is a spring bearing down on slide 28 which maintains the projection slide 8 and piston 6 and 7 in an air tight position over the air passageways entrances, 12 the throttle valve to regulate air through the pure air passageway 18 and 11 a similar valve to regulate air through the carburetor passageway 17.

In Figure II, the throttle valves 11 and 12 are opened or closed simultaneously by the hand lever 45 which is connected to said

valves by the two valve levers 54 and 55 fastened rigidly to the valve stems at 59 and 60 at one end and joined by pins 61 and 57 to the adjustable connecting link rod 44 by their other ends and forming a movable joint thereby, then the connecting rod 46 is connected to the valve levers by pin 57 at 62^a at one end and by pin 58 in the hand lever by the other end, pin 68 is the bearing for the hand lever 45 and 64 the adjustable stop screw, 44 is the adjustable connecting link rod adapted to adjust the relation of said valves to each other and their combined relation to said passageway; 54 is an adjustable valve lever adapted to be so adjusted by lengthening or shortening as to provide a quicker or slower opening or closing time to valve 12 even though both valves are moved simultaneously by the hand lever 45.

In Figure I, 13 is the air inlet port to crank case 5, 14 the air inlet pipe, 15 the exhaust port and pipe, 23 the exhaust discharge heat port leading through pipe 47 and through coil 25 and discharging at 24 to heat the fuel oil in the carburetor, 19 is the secondary air passageways for equalizing the air pressure in the carburetor float chamber 21 to that of the carburetor air passageways 17, 20 the fuel inlet to carburetor, 21 the carburetor float chamber, 53 the needle valve opening for fueling the air, 22 needle valve to regulate the fuel quantity, 26 a screen to mix up the fuel and air traveling through passageway 17 27 and an electric coil 27 to heat the fuel in the carburetor needle valve 53 for starting.

29 is the piston pin, 30 the connecting rod, 31 the crankshaft to reciprocate piston 6 and 7, 62 the crank shaft pin.

In Figure II, 33 is the auxiliary cylinder, 34 the high speed piston, 32 the passageway connecting the auxiliary cylinder 33 to the combustion cylinder 3, 35 the guide for the crosshead 36, 37 piston connecting rod, 38 the rocker arm, 69 the eccentric bushing for increasing or decreasing the compression space of the auxiliary piston 34, 40 the shaft bearing for bushing 69, 41 the lever to operate the eccentric bushing 69 at will, 42 the eccentric gear connecting rod, 39 and 43 are the eccentric gears so timed to move the auxil-

iary piston 34 at an extremely high rate of speed toward the compression space when the combustion piston 6 is traveling slow at the end of its compression stroke, 63 is the eccentric gear shaft, 47 the cylinder head water jacket, 48 the combustion cylinder water jacket, 70 the outside portion of cylinder covering the air inlet port 13, and opening at pipe 14 shown in Fig. II.

10

Operation

In operation, the crank shaft 31 revolves and moves upward towards the combustion cylinder 3 to take in a charge of air into the crank case 5, moving the connecting rod 30, piston pin 29, piston 6 with piston 7 the enlarged portion of the piston 6, the projecting slide 8 and spring 9 bearing down on the slide 28 forcing the slide and piston in opposite directions against the cylinder 4 making the slide 8 air tight and covering over the air passageways 17 and 18 during the upward portion of the stroke thereby shutting off the carburetor from the suction produced by vacuum formed in crank case 5. Arriving at the upper end of the stroke, the port 10 in the projection slide 8 uncovers and opens the port 13 in the upper end of the large air cylinder 4, the air rushing into the vacuum fills the crank case 5, while the air of the upper end of cylinder 4 is open to the atmosphere at all times through port 49. This completes the upward portion of the stroke.

On the return downward stroke of the pistons 6 and 7 with the projection slide 8, entraps and compresses the air in the crank case 5 and uncovers and opens toward the lower end of the cylinder 4 the air passageway 18 first, then transmits a blast of pure air into the combustion cylinder through port 10 in the projecting slide 8, cleansing the combustion cylinder 3 of burnt gases, and then secondly, farther down uncovers and opens and transmits a blast of air through the carburetor passageway 17, a portion of said air blast travels through passageway 19 which equalizes simultaneously the air pressure in the carburetor float chamber 21 to that of the carburetor passageway 17 which permits the fuel to be drawn out from the needle opening 53 of the carburetor by the passing air and mixing thoroughly together when passing through the screen 26 and then transmitted into the combustion cylinder 3 through passageway 17, 27 being an electric heater to heat the fuel in starting, and coil 25 maintains the fuel hot after starting by the fuel in the carburetor float chamber circularizing around the coil 25 continuously, while the exhaust heats the coil.

Now then, the piston 6 and 7 moves upward again and compress the fueled air in the combustion cylinder 3, the moment the combustion piston 6 arrives at its extreme upper end of its stroke, it then travels slow and per end of its stroke, it then travels slow and

is ready for ignition, at this moment, the auxiliary piston 34 shown in Figure II rises, driven by the eccentric gears 39 and 43 which are timed to move at an extremely fast rate of speed the said connecting rod 37 and auxiliary piston 34, which raises the pressure of the combustion in the combustion cylinder 3 through the port 32 so high as to ignite the low grade fueled air instantaneously. A continuation of said operations will cause the engine to fire once every revolution. If high grade fuels are used, any well known electric spark will do, and in such case, the piston 34 is unnecessary.

The speed of the engine can be regulated by the throttle lever 45 arranged to open or close the valves 11 and 12 simultaneously.

The ignition time of the engine can be advanced or retarded by lever 41 which rotates the eccentric bushing 69 around shaft 40 forming a larger or smaller compression space in the auxiliary cylinder 33.

Having described my invention, what I claim and desire to secure by Letters Patent, is:

1. A combustion engine having a cylinder with a large bore and a small bore, an air tight crankcase having means to admit air into the crankcase and enclosing the opposite end of the cylinders, a piston having a large diameter and a small diameter fitted in said cylinders, a projecting slide with one port opening extending from a portion of the large piston, a spring to maintain the projecting slide in close contact with the cylinder, arranged by the reciprocating of the piston to open and close the passageways one at a time, opening the upper passageway first, leading from the large to the small cylinder, then the lower one second, leading from large to small cylinder, through the carburetor, and means to regulate the amount of air passing through each passageway.

2. A combustion engine with a larger air cylinder than the combustion cylinder, an air tight crank case enclosing the opposite end of the cylinder, a piston suitably connected to a crankshaft having a large diameter and a small diameter fitted in said cylinders, means for admitting air into the crankcase, a projecting slide extending from a portion of the large piston with a port adapted by reciprocating of the piston to transmit the crank case air to one of the pair of air passageways at the time leading from the large air cylinder to the combustion cylinder, the upper passageway leading through a throttle valve, the lower one leading through a valve and a carburetor, having a secondary air passageway leading to the carburetor float chamber, and means for manually opening or closing simultaneously said throttle valves in said air passageways.

3. A combustion engine having a larger air cylinder for scavenging than the combustion cylinder for scavenging than the combus-

tion cylinder, means to admit air into the the crankcase by the reciprocation of the large air piston and maintain open to the atmosphere its opposite upper side to prevent compression therein, regulate and transmit at the proper time air through a pair of passageways leading from the larger air cylinder to the combustion cylinder, first blast of pure air into the combustion cylinder, and secondly, a blast of air through the carburetor passageway to the combustion cylinder, and means to equalize, simultaneously, the air pressure in the carburetor float chamber to that of the carburetor passageway when the air is traveling through the carburetor passageway into the combustion cylinder.

4. A combustion engine having a cylinder with a large bore and a small bore, an air tight crank case enclosing the opposite end 20 of the cylinder, a port in the upper end of large cylinder admitting air into the crank case when uncovered by the reciprocation of the piston, having a large diameter and a small diameter and a projecting slide with 25 a port opening extending from a portion of the large piston, arranged by the reciprocation of the piston to open and transmit a blast of air to one passageway at the time located one above the other in the lower end of 30 the larger air cylinder, then closing said passageways during the upward stroke and opening again on the downward stroke, the upper passageway opened first, leading from large to small cylinder, through a valve, the 35 lower one second, leading from large to small cylinder through a valve and a carburetor, and means adaptable to manually open or close simultaneously said valves and adjust the opening or closing time of the throttle 40 valve in the upper air passageway for a faster rate of speed than the throttle valve in the lower carburetor passageway, and means to adjust the relation of said valves to each other and then combine relation to said passageways.

5. A combustion engine having a cylinder with a large bore and a small bore, an air tight crank case enclosing the opposite end of the cylinder, an air inlet port opening the 50 crank case to the atmosphere by the reciprocation of the piston suitably connected to a crankshaft having a large diameter and a small diameter fitting in said cylinder, a projecting slide with a port extending from a 55 portion of the large piston entirely covering the large cylinder air passageways entrances during the upward stroke of the piston, arranged to open said passageways one at a time at the lower end of the stroke, the 60 upper one opening first, leading from large to small cylinder, the lower one second, leading from the large to the small cylinder through a carburetor, a throttle valve in each passageway and means to manually operate simultaneously said valves, having adjustments to 65 regulate their different opening or closing speeds and their combined relation to said passageways, and means for equalizing simultaneously the air pressure in the carburetor float chamber and the gasoline tank to 70 that of the carburetor passageway when the air is traveling through the carburetor passageway into the combustion cylinder.

regulate their different opening or closing speeds and their combined relation to said passageways, and means for equalizing simultaneously the air pressure in the carburetor float chamber to that of the carburetor passageway when the air is traveling through the carburetor passageway into the combustion cylinder.

6. An engine having a series of complete units co-operating on a crank shaft in a line, having in each unit a cylinder with a large bore and a small bore, an air tight crank case enclosing the opposite end of each individual cylinder, having means for admitting air into each individual crankcase, a piston with a large diameter and a small diameter fitted with rings in said cylinder, a piston pin, a connecting rod, a crank shaft connecting them together, a projection slide with a port extending from each of the large piston and communicating with the air passageways placed in the lower end of each large cylinder, arranged to open and close said passageways one at a time, a dual cooperating passageway means for transmitting the air of the upper 80 passageway of all the cylinders through a single throttle valve, then back to the combustion cylinder of the large air cylinder delivering the air first, and secondly, transmit the air of the lower passageway of all the 85 cylinders through a single throttle valve, a carburetor and simultaneously to the secondary air passageway leading to the carburetor float chamber, then back into the combustion cylinder of the large air cylinder delivering the air, and means to manually operate both throttle valves simultaneously.

7. A combustion engine having a cylinder with a large bore and a small bore, an air tight crank case enclosing the opposite end of the cylinder, an air inlet port opening the crank case to the atmosphere by the reciprocation of the piston suitably connected to a crankshaft having a large diameter and a small diameter fitting in said cylinder, a projecting slide with a port extending from a portion of the large piston entirely covering the large cylinder air passageways entrances during the upward stroke of the piston, arranged to open said passageways one at a time at the lower end of the stroke, the upper one open first, leading from the large to the small cylinder, the lower one second, leading from the large to the small cylinder through a carburetor, a throttle valve in each passageway and means to manually operate simultaneously said valves, having adjustments to 115 regulate their different opening or closing speeds and their combined relation to said passageways, and means for equalizing simultaneously the air pressure in the carburetor float chamber and the gasoline tank to 120 that of the carburetor passageway when the air is traveling through the carburetor passageway into the combustion cylinder.

8. The combination of an air pressure charge and cleansing system of a combustion engine cylinder, having means comprising a cylinder, forming a combustion cylinder with an exhaust port and an air pressure cylinder having an air inlet; co-operating with said combustion cylinder, a suitable crankcase secured to said cylinder, a crank-shaft rotatable mounted to said case, a pair of independent air tight passageways leading from the air cylinder to said combustion cylinder, a throttle valve in each passageway, a carburetor arranged to distribute fuel to one passageway, having a sealed float chamber, a suitable piston, having a slide with a port opening, fitted to said cylinder and connected to the crankshaft, adopted to admit air into said air cylinder and to transfer said air through said port to one of said passageways at the time when in motion and of means, adapted to provide air to said float chamber, of a pressure, equal to that of the carburetor passageway, simultaneously when air is transmitted through the carburetor passageway by said port, and a manually operated lever arranged to move both throttle valves.

9. In an air pressure cleansing and charging means of a combustion engine cylinder, the combination of a cylinder, forming a combustion cylinder, having an exhaust opening and an air pressure cylinder, having an air inlet port co-operating with said combustion cylinder, a suitable crankcase fastened to said cylinder, a crankshaft rotatable mounted to said case, a pair of independent air tight passageways leading from the air cylinder to said combustion cylinder, a throttle valve in each passageway, a manually operated lever arranged to move both valves simultaneously, a carburetor arranged to distribute fuel to one passageway, having a sealed float chamber, a suitable piston, fitted to said cylinder and suitably connected to the crankshaft, having a slide with a port opening adapted to admit air into the air cylinder and transfer said air through said port to one of said passageways at the time when in motion and of means, comprising a pair of auxiliary passageways, one leading from the carburetor passageway to said float chamber having a valve to regulate the air volume, the other having a non-return check valve leading from the air cylinder, to the upper end of the fuel tank and means to ignite the cylinder charge at the proper time.

In witness whereof I hereby affix my signature.

JOHN BARLETTA.
